UNITED STATES PATENT OFFICE.

PETER F. McCAFFREY, OF SPOKANE, WASHINGTON.

SIPHON FLUSH-VALVE.

1,176,071.

Specification of Letters Patent. Patented Mar. 21, 1916.

Application filed April 26, 1915. Serial No. 24,054.

To all whom it may concern:

Be it known that I, PETER F. McCAFFREY, a citizen of the United States, residing at Spokane, in the county of Spokane and State of Washington, have invented a new and useful Siphon Flush-Valve, of which the following is a specification.

The device forming the subject matter of this application is a flush tank, and the improvements to which attention is especially directed relate to a means whereby the siphon of the flush tank is started in operation.

The invention aims to provide a novel form of head mounted to move in the short arm of the siphon and constituting a means whereby at the will of an operator, a draining of the tank through the siphon may be initiated.

It is within the province of the disclosure to improve generally and to enhance the utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawings:—Figure 1 is a vertical sectional view of the structure; Fig. 2 is a cross section on the line 2—2 of Fig. 1.

In the drawings, the numeral 62 indi-

cates a tank and the numeral 63 indicates a pipe extended through the tank and forming 40 the long arm of a siphon, the upper end of the pipe being inclosed within a cap 64 forming the short arm of the siphon, the upper end of the pipe being secured to the top 65 of the cap, the pipe 63 having openings 66 located adjacent the top of the cap 64. The piston 67 is guided upon the pipe 63 and surrounds the same, the piston working loosely in the cap 64 and being actuated by a rod 68.

The piston 67 may be lifted by means of the rod 68 and when this operation is carried out, a quantity of water will be lifted, the same flowing into the long arm 63 through the openings 66 therein and serving 55 to effect a starting of the siphon, the upwardly rushing water retaining the piston head 67 elevated, until the tank has been drained.

Having thus described the invention, what 60 is claimed is:—

In a device of the class described, a tank; a pipe extended through the tank; a cap inverted over the pipe and secured to the top of the pipe, the pipe having an opening 65 in its side wall adjacent the top of the cap; a loosely fitting piston surrounding the pipe and surrounded by the cap; and means for operating the piston.

In testimony that I claim the foregoing 70 as my own, I have hereto affixed my signature in the presence of two witnesses.

PETER F. McCAFFREY.
